UNITED STATES PATENT OFFICE.

WILLIAM N. BATES, OF ATLANTIC, IOWA.

DUST-PAN.

SPECIFICATION forming part of Letters Patent No. 651,227, dated June 5, 1900.

Application filed February 23, 1900. Serial No. 6,290. (No model.)

To all whom it may concern:

Be it known that I, WILLIAM N. BATES, a citizen of the United States, residing at Atlantic, in the county of Cass and State of Iowa, have invented certain new and useful Improvements in Dust-Pans; and I do hereby declare the following to be a full, clear, and exact description of the invention, such as will enable others skilled in the art to which it appertains to make and use the same.

This invention provides a long-handled dust-pan which will preclude stooping, stand alone when sweeping the dust therein, and which will fold to facilitate emptying of the dust and enable the pan to be suspended from a nail or like support applied to a wall or partition.

Another purpose of the invention is the provision of a dust-pan of the character and possessing the features aforesaid which will involve a simple, light, durable, cheap, and easily-operable construction and minimum number of parts, the means being of such nature as to be easily applied to any form or pattern of dust-pan now manufactured without requiring any change in the plant or means already provided for constructing the pans.

The invention also consists of the novel features, details of construction, and combination of the parts which hereinafter will be more fully disclosed and finally claimed, and for this purpose and also to acquire a knowledge of the merits of the invention and the structural details of the means whereby the results are attained reference is to be had to the appended description and the drawings hereto attached.

While the essential and characteristic features of the invention are necessarily susceptible of modification, still the preferred embodiment of the invention is illustrated in the accompanying drawings, in which—

Figure 1 is a perspective view of a dust-pan, showing the application of the invention. Fig. 2 is a vertical longitudinal section. Fig. 3 is a side elevation illustrating the disposition of the parts when the pan is folded. Fig. 4 is a rear perspective view of the foot-piece and attached parts.

Corresponding and like parts are referred to in the following description and indicated

in all the views of the drawings by the same reference characters.

The dust-pan 1 may be of any form, make, or pattern and is shown to demonstrate the application and workings of the invention, the latter consisting, essentially, of the handle 2 and the parts coöperating therewith to admit of the pan folding and having a bracing connection with the handle when in working position.

A foot is applied at a central point to the back of the pan to hold the rear portion elevated, whereby the front edge is held in close contact with the floor, so as to enable the sweepings being readily brushed into the pan. This foot is preferably formed of a strip or oblong blank of metal having its end portions bent, as shown at 3 and 4, and the intermediate portion inclined, as shown at 5, and constitutes a brace. The bent terminal 3 is riveted or otherwise secured to the back of the pan, and the bent portion 4 is constructed to obtain a broad bearing upon the floor, so as to prevent tilting or sidewise movement of the pan when placed in position to receive the sweepings. By having the foot stand rearwardly from the pan the latter is braced and the handle 2 held in an upright position when the device is left unattended, the parts being so disposed and proportioned that the dust may be swept into the pan without any fear of tilting or upsetting the article and spilling the sweepings upon the floor.

The handle 2 has pivotal connection with the foot, its lower end being formed with a kerf 6 to receive a lug 7, projecting rearwardly from the foot, said lug being formed in the most convenient manner by bending a metal blank or strip intermediate of its ends into right-angular form and securing one of the ends to the foot or part 5 by means of a rivet, soldering, or the like and pivotally connecting the other bent end with the handle in the manner stated.

In order to maintain the handle in an upright position, means are provided and interposed between it and the pan, the same consisting of a bail 8, having its end portions pivotally connected with the sides of the pan a short distance from the back and having a loop or eye 9 at a central point to receive and

run upon the handle 2. This loop or eye 9 is formed by bending a portion of the wire comprising the bail at a central point and intertwisting the parts, as shown at 10, so as to 5 maintain the form of the eye. The eye 9 is bent at an obtuse angle with reference to the plane of the bail and occupies a position about at a right angle to the length of the handle. A spring-catch 11, fitted to the handle 2, co- 10 operates with the bail and holds it in fixed position with reference to the handle when the latter is turned into an upright position or about at a right angle to the plane of the pan. The catch 11 consists of spring-wire 15 having its lower end seated in a saw-cut provided in a side of the handle 2, the upper end of the wire being formed into a loop 12 and finger-piece 13, a pin 14 extending across the saw-cut, engaging with the closed end of the 20 loop 12, and preventing outward displacement of the upper or free end of the spring-catch. When the pan is turned so as to occupy a position approximately at a right angle to the handle 2, the part 10 of the bail enters the 25 looped portion 12 of the catch and holds the handle and pan in the position shown in Figs. 1 and 2. When it is required to fold the pan, the finger-piece 13 is pressed upon, thereby disengaging the catch from the bail, and upon 30 lifting the handle 2 the pan will automatically fold and assume the position shown in Fig. 3, when the device can be suspended from a nail or analogous device by means of an eye 15, applied to the upper end of the handle. The 35 pan may be turned into an operative position by bringing its lower edge in contact with the floor and pressing down upon the handle, which will cause the loop or eye 9 to run upward upon the handle 2 until engaged by the 40 looped portion 12 of the spring-catch, when the parts will be held in the relation shown in Figs. 1 and 2.

It will be noticed that the handle is pivoted directly to the foot in the rear of the pan and 45 is braced from the latter by means of the bail. Hence very little force is required to hold the handle in an upright position, and the weight of the handle does not come directly upon the pan. It will also be observed that the handle 50 and adjunctive parts can be readily applied to any make or style of pan by simply attaching the foot to the back of the pan and the free ends of the bail to the sides thereof, such attachment being readily effected by any person skilled in the handling of tools. 55

For the purpose of holding the handle and pan absolutely rigid when the parts are disposed as in Fig. 2 the handle is formed near its lower end with a notch 16 to receive the 60 upper rear edge 17 of the pan. This construction provides a slot-and-tongue connection which effectually obviates independent play of the parts when the pan is supported to receive the sweepings.

65 Having thus described the invention, what is claimed as new is—

1. In combination with a dust-pan, a foot

secured at its upper end to the back of the pan and inclining downwardly and rearwardly and terminating in a horizontal widened portion to obtain an extended bearing upon the floor, a handle pivotally connected to the inclined portion of said footpiece, a bail constituting a brace having pivotal connection with the pan a short distance in advance of the back and having a running connection with the handle, and means for securing the running end of the bail to the handle when the latter and pan have assumed a position about at a right angle to each other, substantially as described. 7c 75 80

2. In combination with a dust-pan, a foot secured at its upper end to the back of the pan and inclining downwardly and rearwardly and terminating in a horizontal widened portion to obtain an extended bearing upon the floor, a lug projecting rearwardly from the inclined portion of the foot, a handle having pivotal connection with said lug, a bail having pivotal connection with the pan 90 and a running connection with the handle, and means applied to the handle for securing the bail when the pan has been turned to occupy a position about at a right angle to the handle, substantially as described. 95

3. In combination with a dust-pan, a foot secured at its upper end to the back of the pan and inclining downwardly and rearwardly and terminating in a horizontal widened portion to obtain an extended bearing upon the floor, a handle pivotally connected to the inclined portion of said footpiece, a spring-catch applied to the handle and having a free end bent to form a loop constituting a receiving portion and upper and lower stops and a finger-piece projecting outwardly and upwardly beyond the loop, and a wire bail having its lower end pivotally connected with the pan and its upper end bent to form an integral eye embracing the handle and co-operating with the catch, substantially as described. 100 105 110

4. In combination with a dust-pan, a foot secured to the back thereof and inclining rearwardly and terminating in a widened portion to rest upon the floor, a metal piece bent at a right angle and secured at one end to the foot and having its opposite end constituting a lug, a handle receiving the lug at its lower end and pivoted thereto, a spring secured at one end to the handle and having its opposite end bent to provide a loop, and a bail having pivotal connection with the pan and having its middle portion bent to provide an eye, the latter receiving the handle and adapted to run thereon and engage with the looped portion of the spring, substantially as set forth. 115 120 125

In testimony whereof I affix my signature in presence of two witnesses.
